Specification of Letters Patent.

Patented Feb. 6, 1912.

Application filed August 3, 1911. Serial No. 642,067.

To all whom it may concern:

Be it known that we, FREDERICK E. COYNE, SAMUEL G. TAYLOR, Jr., and JOHN W. ESKHOLME, citizens of the United States, and 5 residents of Chicago, in the county of Cook and State of Illinois, have invented certain new and useful Improvements in Railway Mail Catching and Delivering Apparatus; and we do hereby declare that the following 10 is a full, clear, and exact description thereof, reference being had to the accompanying drawings, and to the letters of reference marked thereon, which form a part of this specification.

15 This invention relates to improvements in railway mail catchers and deliverers, and consists of the matters hereinafter described and more particularly pointed out in the appended claims.

20 The invention, as disclosed herein, is particularly applicable to railway catchers and deliverers of the type described in Letters Patent No. 884,868, dated April 14, 1908, and No. 939,557, dated November 9, 1909, 25 granted to W. T. Sebree, in which the mail sacks or pouches are adapted to be caught in chain nets carried respectively by the mail car and by a crane at the side of the road bed, said nets being secured to frames 30 hinged respectively to the car and to the road side crane.

35 The device includes supporting members, one for the car and one for the road side crane, adapted for the support of the mail pouches in alinement with the respective chain nets within which they are to be caught.

40 The invention relates particularly to an improved construction of the nets used in such an apparatus and to means for attaching the same to their supporting frames, and its advantages will appear clearly as we proceed with our specification.

45 In the drawings—Figure 1 is a view representing in front elevation the nets carried respectively by the car and by the road side crane in the position which they occupy at the time the mail sacks are adapted to be caught. Fig. 2 is a view representing a section through the car net on the line 2—2 of Fig. 1, the dotted line indicating the position of the net when distended at the time of catching the mail sack. Fig. 3 is a partial 50 plan view of the chain net on an enlarged

scale; Fig. 4 is a diagrammatic plan view 55 of the car side chain net; Fig. 5 is a detail fragmentary view showing the manner of securing the chains comprising the net together at the points where they intersect; Fig. 6 is a detail side elevation of a device 60 by means of which the net is secured to its frame.

Referring now in detail to the drawings, 10 indicates a car to the side of which, adjacent the usual door opening there is hinged 65 a frame 11, to which is secured a chain net 12. 13 indicates an upright road side crane to which is hinged a rectangular frame 14 carrying a chain net 15. At the top of the crane 13 is secured an arm 16 adapted for 70 the suspension of a mail bag or bags in line with and at an elevation to be caught by the chain net 12 carried by the car. To the car side net frame 11 is secured an arm 17, which is adapted to support a mail bag in 75 line with the road side net frame and in position to be caught in the net thereof. These general features of construction are substantially as described in the patents above referred to and need no further description here.

The nets for catching the mail pouches are made of a plurality of lengths of chain, said lengths being arranged in two sets, the chain lengths of one set being arranged at 85 an angle to those of the other set. As shown in the drawings, the one set of chain lengths are arranged in parallel, horizontal lines, while those of the other set are arranged in parallel vertical lines. The ends of the 90 chain lengths are connected to the net supporting frame, and the net comprised by the chain lengths is larger than the associated frames so that when distended it may hang down below the frame in the form of a 95 pocket as shown by the dotted lines in Fig. 2.

Referring first to the car side net 12, the same consists of a plurality of parallel vertical lengths of chain 12^a and a plurality of horizontal lengths of chain 12^b arranged to 100 intersect the said vertical lengths of chain. As shown in the drawings, there are seven vertical lengths 12^a of the chain and four horizontal lengths 12^b. At each point of intersection of the horizontal and vertical chain lengths, a link *a* of the horizontal length of chain extends loosely through a link *b* of the vertical length of chain, as clearly seen in 105

Figs. 3 and 5. The vertical link b has its side members bent inwardly, so as to decrease the space between them and thus prevent the possibility of the next adjacent horizontal link a' or a'' at either side of the horizontal link a passing through the link b . By this construction, lateral separation of the vertical lengths of chain to a limited extent is permitted at their points of intersection and connection with the horizontal lengths of chain thus providing a flexibility of movement between said lengths of chain which tends to ease up the force of the jar of the mail pouch when it strikes the chain, and thus reduce the effect of the force of the impact. By the flexible connection described, a limited relative yielding movement of the chain lengths comprising the net, after the net has assumed the form of a pocket, is made possible, thus relieving the rigidity of the shock and facilitating the operation of the device.

As shown in the drawings, the upper two horizontal chain lengths 12^b are shorter than the lower horizontal chain lengths 12^c . Likewise the outer vertical chain lengths 12^a are shorter than the intermediate vertical chain lengths 12^d . All of the chain lengths are longer than the distances spacing the respective frame bars to which they are connected. By this arrangement the net is capable of assuming a bag-like shape, such as shown by dotted lines in Fig. 2, when it is struck by the mail pouch, said net forming a pocket c below the level of the lower frame bar 14^a into which the mail sack drops after the force with which it strikes the net has been exhausted in expanding the same.

The links at the end of the chain are connected to the frame as follows: On the inner face of each of the bars comprising the net supporting frame, is formed a plurality of pairs of projecting apertured lugs 20, the apertures in said lugs being arranged so that they are in line. A rod 21 extends through the apertures in said lugs and is prevented from longitudinal movement with reference to said lugs by means of cotter pins in each end. The pairs of lugs are spaced apart a distance substantially equal to the distance that the chains to which they are connected are to be spaced, and the lugs of each pair are spaced from each other a distance sufficient to permit the links at the ends of the chains to be inserted between them flatwise. Each rod 21 extends through the end links of chain lengths which it is intended to secure to the associated frame member.

It is apparent that the means described for attaching the chain lengths of the net to the net frame provides a construction, by means of which the net may be easily detached from its frame when renewals or re-

The road side net 15 is similar in construction to the car side net but is preferably made larger as shown in the drawings. Said net has ten vertical chain lengths 25^a and six horizontal chain lengths 26^b . The six intermediate vertical chain lengths 25^a are longer than the two chain lengths 25^b at either side. Likewise the three lower horizontal chain lengths 26^a are longer than the three upper ones, 26^b . Like means is used for attaching the chain ends to the frame, 27 indicating the spaced pairs of apertured lugs, and 28 the rod extending through the apertures in said lugs and through the links engaged between the said pairs of lugs.

We claim as our invention:

1. In a device of the class described, in combination with an open frame, a net supported thereby comprising a plurality of chain lengths arranged in two sets, the chain lengths of one set extending at an angle to and intersecting the chain lengths of the other set, and the links of one set of chain lengths at the points of intersection extending loosely through the links of the other set. 70
2. In a device of the class described, in combination with an open frame, a net supported thereby comprising a plurality of chain lengths arranged in two sets, the chain lengths of each set being parallel and those of the one set extending in substantially vertical lines and those of the other set extending in substantially horizontal lines, the links of one set of chain lengths at the points of intersection extending loosely through the links of the other set. 90
3. In a device of the class described, in combination with an open frame, a net supported thereby comprising a plurality of chain lengths arranged in two sets, the chain lengths of each set being substantially parallel, and one set of chain lengths extending in horizontal lines and the other set, in vertical lines, the chain lengths of one set intersecting the chain lengths of the other set, and the links of the set of horizontal chain lengths at the points of intersection extending loosely through the links of the other set. 105
4. In a device of the class described, in combination with an open frame, a net supported thereby comprising a plurality of chain lengths arranged in two sets, the chains of each set being substantially parallel, and one set of chain lengths extending in horizontal lines and the other set in vertical lines, the chain lengths of one set intersecting the chain lengths of the other set, and the links of the set of horizontal chain lengths at the points of intersection extending loosely through the links of the other set, each link of the vertical set of chain lengths through which a link of the hori- 110
- 125
- 130

zontal set extends having its side members bent inwardly to prevent the adjacent links of the horizontal chain lengths from passing between said lateral members.

5. In a device of the class described, in combination with an upright open frame, a net comprising a plurality of chain lengths arranged in two sets and secured at their ends to said frame, the chain lengths of one set extending in substantially vertical lines and the chain lengths of the other set extending in substantially horizontal lines, and the chain lengths of the horizontal set nearer the lower part of said frame being 10 longer than those nearer the upper part of said frame and the chain lengths of the vertical set nearer the vertical median line of said frame being longer than the chain lengths nearer the vertical sides of said 15 frame.

6. In a device of the class described, in combination with an upright open frame, a net comprising a plurality of intersecting chain lengths arranged in two sets and secured at their ends to said frame, the chain lengths of one set extending in substantially vertical lines and the chain lengths of the other set extending in substantially horizontal lines, and the chain lengths of the 20 horizontal set nearer the lower part of said frame being longer than those nearer the upper part of said frame, and the chain lengths of the vertical set nearer the vertical median line of said frame being longer than the chain lengths nearer the vertical sides 25 of said frame, and the links of the horizontal

chain lengths at their points of intersection with the vertical chain lengths extending through the associated intersecting vertical links. 40

7. In a device of the class described, in combination with a frame comprising top and bottom members and two side members, a net consisting of two sets of intersecting flexible members, the flexible members of one set extending at an angle to the flexible members of the other set, each flexible member having links at its ends for attachment to the frame members, each frame member being provided with a plurality of pairs of 45 lugs having apertures arranged in a line parallel to said frame member, there being a pair of said lugs for the end of each flexible member attached to said frame member, and the lugs of each pair being spaced apart to 50 receive a link at the end of an associated flexible member, and a rod for each frame member extending through the apertures in said lugs and through said links, said rod being provided with removable means for 55 retaining it in position.

In testimony, that we claim the foregoing as our invention we affix our signatures in the presence of three witnesses, this 24th day of July, A. D. 1911.
